CLAIM

The ornamental design for a detection device, as shown and described.

DESCRIPTION

FIG. 1 is a front, top perspective view of a detection device showing our new design;

FIG. 2 is a front, bottom perspective view thereof;

FIG. 3 is a front elevation view thereof; the rear view of the detection device is a mirror image of the front view;

FIG. 4 is a left side elevation view thereof; the right side view of the detection device is a mirror image of the left side view;

FIG. 5 is a top plan view thereof; and,

FIG. 6 is a bottom plan view thereof.

The oblique shading lines in the claimed design illustrate surfaces that are transparent.

1 Claim, 6 Drawing Sheets
